UNITED STATES PATENT OFFICE.

ALBERT SCHEIDECKER, OF BASEL, SWITZERLAND.

METHOD OF ATTACHING INVERTED INCANDESCENT MANTLES TO HOLDERS.

1,079,955.

Specification of Letters Patent.

Patented Dec. 2, 1913.

Application filed April 9, 1913. Serial No. 759,909.

To all whom it may concern:

Be it known that I, ALBERT SCHEIDECKER, a citizen of the Swiss Republic, residing at Basel, in Switzerland, have invented certain new and useful Improvements in the Method of Attaching Inverted Incandescent Mantles to Holders, of which the following is a specification.

The method heretofore adopted for attaching inverted incandescence mantles to the annular holders with which they are fitted, consists in drawing the mantle on to a mandrel or block, which is provided with marks, and then loosely attaching an asbestos thread to the mantle above its edge or mouth, in a position indicated by that mark on the mandrel which indicates the length which the mantle is to have, the edge of the mantle being then folded back over the 20 thread, sewn by hand and cut straight, whereupon the mantle is stripped off the mandrel and turned, and then replaced on the mandrel for the purpose of smoothing the seam. The mouth of the mantle is then 25 drawn on to the annular holder and the thread is drawn tight in the groove of the holder, and tied, the folds produced by this operation being finely smoothed out. As the holder is usually made of magnesia and 30 is consequently fragile, it will be apparent that the process described must be carried out with great care in order to avoid injury to the holder as well as injury to the mantle.

The object of the present invention is to 35 provide a method which is much more simple and reliable, and obviates the disadvantage of the known method.

According to the invention, the mantle turned inside out, is drawn on to a mandrel 40 reduced in diameter at one end for a distance equal to the length which the mantle is to have, and the mantle is held on this mandrel by hand, or by means of a spring ring. The edge of the mantle, projecting 45 beyond the shoulder of the mandrel is then folded back and the superfluous part thereof is cut off, whereupon the holder is slipped over the mantle till it abuts on the shoulder of the mandrel, and the folded edge of the 50 mantle still projecting beyond the shoulder, is turned back over the holder and fastened thereto. As the mantle remains stretched during its attachment to the head of the

holder, the formation of folds is wholly avoided.

The invention is illustrated in the accompanying drawing, in which:—

Figure 1 shows the mantle turned inside out, placed on the mandrel (first operation). Fig. 2 shows a subsequent stage of 60 operation, the holder (shown in section) having been slipped on to the mandrel after the folding back of the edge of the mantle (second operation). Fig. 3 shows the mantle finally secured to the holder, but still 65 turned inside out. Fig. 4 is a sectional elevation, drawn to a larger scale illustrating the operation of attaching the mantle to its holder. Fig. 5 shows the mantle after it has been pulled through the holder from 70 the position shown in Fig. 3, the mantle at this stage being ready for reduction to ash and collodionization.

The appliance illustrated consists of a cylindrical mandrel having an upper reduced portion *a*, and a lower part *b* of larger diameter, with a shoulder *c* formed, at the junction of these two parts and groove *d*, directly below this shoulder.

The method of attaching the mantle to 80 its holder will now be described with reference to the drawing.

In the first instance the mantle *A* is turned inside out and drawn onto the mandrel, at the reduced end, so that its edge is somewhat below the groove *d* on the thicker part *b* of the mandrel. The spring ring *e* is then slipped over the part *a*, and pushed down till it springs into the groove *d* and holds the mantle securely on the mandrel. The 85 edge of the mantle is then folded back over the spring ring, and if necessary tied, above the ring, and any superfluous material at the edge is cut off. Then the annular holder *B* is slipped over the part *a*, so that its head 90 *B*¹ rests against the shoulder *c* of the mandrel, whereupon the spring ring together with the folded part of the mantle surrounding it, is slipped upward on to the holder, as indicated by the arrows in Fig. 2, 100 so that the spring snaps into the groove in the holder. By this means the mantle is firmly attached to the holder. It is then only necessary to pass the mantle *A* through the holder *B* as indicated by the arrow in 105 Fig. 3.

The above described operations are extremely easy and rapid. By gripping the mantle A to the holder B by means of the spring ring e, instead of tying it with thread as heretofore and producing an irregular puckered fold, the mantle is held smoothly on the holder and a large amount of injury and scrapping is avoided. The mantle may, however, be attached without the aid of the 10 spring ring, by holding the folded part by hand, and slipping the holder over it, the folded edge being then folded over the holder and tied thereto by means of asbestos string, the manipulation is however, greatly 15 facilitated by using the spring.

What I claim as my invention and desire to secure by Letters Patent of the United States is:—

1. The method of attaching an incandescence mantle to an annular holder, which 20 consists in drawing the mantle on to a mandrel having a reduced end whereby a shoulder is produced, the mantle being drawn on to said reduced end and extending somewhat beyond said shoulder, slipping the annular holder over the mantle on said reduced end till said holder abuts on said shoulder, folding back, over the holder, that 25

part of the mantle which extends beyond said shoulder, and attaching said folded back part to the holder. 30

2. The method of attaching an incandescence mantle to an annular holder having an external groove which consists in drawing the mantle on to a mandrel having a reduced end whereby a shoulder is produced, the mantle being drawn on to said reduced end and extending somewhat beyond said shoulder, placing a spring ring around the mantle part which projects beyond said shoulder, folding back the edge of the mantle to embrace said ring, slipping the annular holder over the mantle on said reduced end till it abuts on said shoulder, and drawing the folded part of the mantle 40 together with the spring ring over said holder so that the ring snaps into the groove of the holder. 45

In witness whereof I have signed this specification in the presence of two witnesses. 50

ALBERT SCHEIDEGGER.
